UNITED STATES PATENT OFFICE.

FRANCIS J. TORRANCE, OF PITTSBURG, PENNSYLVANIA.

DESIGN FOR A WASH-STAND.

SPECIFICATION forming part of Design No. 17,950, dated December 13, 1887.

Application filed September 8, 1887. Serial No. 249,179. Term of patent 7 years.

To all whom it may concern:

Be it known that I, FRANCIS J. TORRANCE, a citizen of the United States, residing at Pittsburg, in the county of Allegheny and State

of Pennsylvania, have invented a certain new and original Design for Wash-Stands; and I do hereby declare the following to be a full, clear, and exact description of the invention, reference being had to the accompanying drawing, which forms part of this specification.

My invention has relation to a design for wash-stands; and my invention consists in the novel ornamental configuration hereinafter described and claimed, and illustrated in the accompanying drawing, wherein the figure illustrates a wash-stand top and back in perspective according to my design.

The shape of the top A of the wash-stand is that of a parallelogram with rounded corners *a a* and circular basin-holes B B. Around each of the basin-holes B B is formed a raised plain molding, *b b*, which follows the outline of the top A, and may be slightly rounded off at its front edge, as at *b'*.

The back of the stand consists of a flat slab, C, set up at right angles to the top A, and finished at each end with an angle curve, D, as shown.

The principal feature of my design consists in the configuration of the top A, having the rounded corners *a a*, and the back having the angle curves D at each end.

I claim—

The design for a wash-stand illustrated in the accompanying drawing and herein described, consisting, essentially, of the top A, having rounded corners *a a*, and the back piece, C, having its ends finished with angle curves D, said top and back being at right angles to each other.

In testimony that I claim the foregoing I have hereunto set my hand this 3d day of September, 1887.

FRANCIS J. TORRANCE.
